UNIFORM CAP WASHING AND DRYING
FORM

Samuel Sugar, Chicago, Ill.

Application April 22, 1942, Serial No. 439,972

4 Claims. (Cl. 223—24)

This application relates to forms to facilitate washing of uniform cap covers of the type having a wide, flat band and an enlarged crown portion, and to maintain such cap covers in smooth condition during drying.

White uniform caps are required to be worn by officers during certain seasons, and as the caps are easily soiled it is customary to use caps comprising a frame and a white cap cover which fits over the frame. When the cap cover becomes soiled after use, the cover is removed and washed, and must then be pressed or blocked back into shape. Cap covers ordinarily comprise a large flat top or crown portion and a band portion of smaller circumference. Due to the greater size of the crown portion than of the band portion, solid blocking forms are unsatisfactory, and it has heretofore been proposed to employ stretching forms comprising sheet metal members which can be collapsed together for insertion into the cap cover and then expanded by means of internal bracing members to stretch the cap to the desired extent. Such collapsible metal forms are cumbersome to operate due to the number of parts and the necessity for accurate adjustment of the collapsible members, and are bulky to carry about. Also the metal forms become corroded and tend to collect dust and dirt so that the cap cover applied thereon becomes discolored.

It is an object of the present invention to provide an inexpensive and light, yet sturdy, and highly practical form for maintaining the shape of cap covers during washing and drying.

It is a further object to provide a form for use in washing and drying cap covers which employs only a minimum of metal, or no metal at all, so that the problem of avoiding corrosion of cap cover forms and discoloration of cap covers is substantially eliminated.

It is an additional object of the invention to provide a cap cover form which may be inserted into a cap cover as a unit without the necessity for collapsing, unfolding, and adjusting of internal bracing members, and which serves to hold the cap cover in shape during washing and drying.

Other objects and advantages of the invention will appear from a consideration of the following detailed specification.

Accordingly, for a more complete understanding of the invention, reference is made to the accompanying drawing, in which

Fig. 1 is a side elevation showing a cap cover stretched on my improved cap cover form;

Fig. 2 is a perspective view of my improved cap cover form;

Fig. 3 is a sectional elevation taken along the line 3—3 of Fig. 2, showing my improved cap cover form with a cap cover thereon, and showing in detail the stiffened connecting member holding the crown-shaping portion and the band-shaping portion together as a unit.

In the embodiment of the invention shown in Fig. 1, the washing and drying form 1 (shown in dotted lines) is disposed in a conventional cap cover 2 comprising a top or crown portion 3 of generally circular or oval outline, a band portion 4 of a circumference smaller than that of the top or crown portion, and an intermediate portion 5 connecting the crown portion 3 and the band portion 4.

As shown most clearly in Figs. 2 and 3, the form 1 of my invention comprises a crown-shaping spring ring 6, a band-shaping frame or band 7, and a connecting member 8 holding the ring 6 and frame 7 in spaced relation. The spring ring 6 is a flat, flexible, relatively narrow band of a circumference substantially equal to the inside circumference of the crown or top portion 3 of a cap cover 2. As shown in Fig. 3, the spring ring 6 extends along the seam 9 between the top 3 of the cap cover 2 and the intermediate portion 5, and resiliently holds the top or crown 3 flat and smooth for washing and drying. The ring 6 may comprise a lacquered strip of steel in the form of a ring. Alternately the ring 6 may be of metal wrapped in waterproof sheet material, or may be formed of other springy material, such as a plastic, e. g., Celluloid, the flexibility being such that it can readily be introduced into a cap cover 2 through the narrow band portion 4.

The band-shaping frame or band 7, comprising a second part of the form 1, has a width and a circumference substantially equal to the width and inner circumference of the cap cover band 4. This frame 7 desirably is formed of a stiff strip 10 of waterproof, plastic material, such as Celluloid or similar material secured in the form of a ring by clips or rivets 11 extending through the overlapping ends of the strip 10. The frame 7 must be formed of material of sufficient strength to prevent excessive shrinking of the cap cover band 4 when the frame 7 is in place in the band 4 during drying.

Connecting the crown-shaping ring 6 and the band-shaping frame 7 is a wide strip 12 of flexible, waterproof material. As shown best in Fig. 3, the strip 12 comprises a ply 13 of relatively heavy duck and a second ply 14 of washable

leatherette. As shown in Figs. 2 and 3, the plies are held together by stitching 15 adjacent the edges of the assembled plies. A hem 16 is formed by stitching 17 spaced from one end of the strip 12 to receive the crown-shaping ring 6. The strip 12 may have a width of about 3 to 9 inches at the end adjacent the hem 16, and about 2 to 6 inches at the other end. These dimensions are, however, only exemplary and are not to be understood as in any way to limit the invention. Suitably the strip 12 has a length substantially equal to the sum of the widths of the band 4 and intermediate portion 5. A wide, flat stiffener member 18 is secured between the plies 13 and 14 of the strip in the center portion of strip 12, with one end adjacent the inner edge of hem 16 and the other end terminating at the lower edge of strip 12, by a row of stitching 19 extending through the plies and stiffener.

The strip 12 is secured to the band-shaping frame 7 by stitching 20 which extends through the plies 13 and 14, stiffener 18, and the overlapping ends of strip 10. This stiffened strip 12 holds the ring 6 in spaced relation to the frame 7 so that when the form 1 is in place in a cap cover 2, with the stiffened strip 12 at the front of the cap cover, the intermediate portion 5 of the cap cover in the front portion of the cap will be held smooth.

Also, the strip 12 connects the ring 6 and frame 7 so that they may be easily and quickly inserted as a unit into a cap cover 2 for washing and drying, and may be quickly removed from the cap cover 2 without creasing or crumpling the cap cover. To apply the form 1 to a cap cover 2, the spring ring 6 is flexed and passed through the frame 7. The frame 7 is then positioned in the band 4 of the cap cover 2, with the strip 12 at the front of the cap cover 2. The crown-shaping ring 6 is flexed and passed back through the frame 7, and then expands into contact with the seam 9 between the crown portion 3 and the intermediate portion 5 of the cap cover 2 to hold the crown smooth and taut. The outer surface of the frame 7 is in contact with the inner surface of the band 4 of the cap cover 2, and holds the cap-cover band 4 smooth and prevents excessive shrinking during washing and drying. The relatively wide connecting strip 12 between the ring 6 and the frame 7 stretches the intermediate portion 5 at the front of the cap so that the intermediate portion 5 dries smooth and free from wrinkles. When the cap cover 2 has dried after washing, the form 1 is removed by grasping the crown-shaping ring 6 and pulling it outwardly through the opening in the band-shaping frame 7. The band-shaping frame 7 itself is then withdrawn. On removal of the band-shaping frame 13, it will be found that the cap cover 2 has dried smoothly, with the top 3 and band 4 smooth and wrinkle-free, and with the intermediate portion 5 at the front of the cap cover 2 also smooth and free from wrinkles.

Thus it will be seen that I have provided a cap-cover form which is extremely simple in construction and inexpensive to construct, and which, moreover, can be formed of materials which are readily available notwithstanding the ban on the use of metals. Also, due to the small use of metal parts, the tendency to discolor cap covers with which it is used is substantially eliminated. The form is simple to use since it can be inserted as a unit into a cap cover without the juggling of collapsible parts and internal

bracing arms, and gives highly satisfactory results.

It is not intended that the description heretofore given of the invention and/or the showing thereof set forth in the drawing is limiting in any respect of the monopoly claimed by applicant. It is on the contrary intended that all claims hereinafter allowed, whether made initially or to be added (assuming that they are properly supported by the drawing and/or specification and/or claims originally made herein), shall be the measure of the scope of the invention herein set forth. Accordingly, and with the foregoing in mind, what is claimed as new and is desired to be secured by Letters Patent is (remembering that claims broader than those now included may hereafter be found properly includable herein):

I claim:

1. A removable form for uniform cap covers comprising a flat, narrow, flexible spring ring of circumference corresponding to the inside circumference of the crown or top portion of a cap cover, a stiff band or frame of a width and circumference corresponding to the width and interior circumference of a cap-cover band, and a stiffened member connecting the wide band and the narrow spring ring for insertion of the band and ring as a unit into a cap cover to hold the cap band and cap crown or top portion smooth during washing and drying, and removal as a unit, said stiffened member maintaining the band and ring in predetermined spaced relation.

2. A removable form for uniform cap covers comprising a flexible spring ring of circumference corresponding to the inside circumference of the crown or top portion of a cap cover, a stiff band or frame of circumference corresponding to that of the inside of the cap-cover band, a stiffened strip rigidly secured adjacent one end to the band or frame and pivotally connected to the spring ring to maintain the band and ring in spaced relation for insertion as a unit into a cap cover with the spring ring extending along the inside of the rim of the cap cover and the stiff band or frame in contact with the inside of the band to shape the top and the band, respectively, of the cap cover.

3. A removable form for uniform cap covers comprising a flexible spring ring of circumference corresponding to the inside circumference of the crown or top portion of a cap cover, a stiff band or frame of circumference corresponding to that of the inside of the cap-cover band, a wide, flexible strip connecting the ring and the band or frame, and a stiffener for the strip having one end rigidly connected to the band or frame to maintain the band and ring in spaced relation for insertion as a unit into a cap cover, with the spring ring extending along the inside of the crown or top of the cap cover and the band or frame in contact with the inside of the cap-cover band to maintain the top of the cap cover and the cap-cover band, respectively, smooth during washing and drying.

4. A removable form for uniform cap covers having a band, an intermediate connecting portion and a top or crown portion, said form comprising a flat, relatively narrow, flexible spring ring of circumference corresponding to the inside circumference of the crown or top portion of a cap cover, a stiff band or frame of width and circumference substantially equal to the width and circumference of the inside of the cap-cover band, a wide, flexible strip having one end sewed to the band or frame and having a hem at the

opposite end in which the flexible spring ring is inserted, a stiffener for the wide, flexible strip having one end rigidly connected to said stiff band or frame and having the other end terminating adjacent the hem of the flexible strip to maintain the band and ring spaced adjacent the wide strip a distance approximately equal to the width of the intermediate connecting portion of the cap cover, said wide strip and stiffener holding the band and ring together for insertion as a 10

unit into a cap cover, with the flexible spring ring extending along the inside of the crown or top of the cap cover and the band or frame in contact with the inside of the cap-cover band to maintain the top of the cap cover, the cap-cover band, and the intermediate connecting portion of the cap cover adjacent the wide, flexible band smooth during washing and drying.

5 SAMUEL SUGAR.
